ADJUSTABLE STANDARD

Paul C. Calissi, Philadelphia, Pa.

Application July 12, 1932. Serial No. 622,050

4 Claims. (Cl. 240—81)

This invention relates to adjustable lamp standards and more particularly to a universally adjustable standard for what are known as "sun-ray" lamps.

As those familiar with the art to which this invention appertains well know, in order to provide for the most efficient use of the so-called "sun-ray" lamps, the latter must be arranged for adjustment into various positions to most satisfactorily suit the demands of the particular user of the lamp. Furthermore, the adjustment should be easily accomplished without necessitating the use of numerous and complicated devices for effecting the necessary adjustment and for maintaining the lamp in any particular adjusted position. Heretofore and prior to this invention various attempts have been made from time to time to secure a positionally adjustable "sun-ray" lamp but the various expedients employed to this end have not proved entirely satisfactory, have measurably increased the expense of the unit, and have not been able to afford a maximum degree of positional adjustment.

It is among the principal objects of the present invention to provide in a standard for a "sun-ray" lamp or the like a readily operable device or mechanism for effecting a substantially true universal adjustment of the lamp.

A further and more specific object of the invention is the provision of a standard having handle-operated means for shifting the lamp in any desired direction, the said means being so arranged and so designed as to securely maintain a lamp in any given or required adjusted position.

Still further objects of the invention are the provision of a compact, simple and inexpensive ball and socket joint between the vertically extending pedestal and the laterally extending arm of the "sun-ray" lamp whereby the latter may be not only rotated about an axis extending diametrically through the ball of the joint but also shifted angularly with respect to the horizontal axis of the socket for said ball, the ball and socket joint having operatively associated therewith readily adjustable spring-pressed means for effecting the maintenance of said laterally extending arm in any desired adjusted position. Other objects of the invention relating to details of construction and advantages resulting therefrom will be apparent more fully hereinafter.

The invention consists substantially in the combination, construction, arrangement and relative location of parts, all as described more fully hereinafter, as shown in the accompanying

drawing, and as finally pointed out in the appended claims. In the said accompanying drawing:

Figure 1 is a side elevational view of a "sun-ray" lamp constructed in accordance with and embodying the features of the present invention;

Figure 2 is a perspective view of the lamp showing the same in an adjusted position other than that shown in Figure 1;

Figure 3 is a view showing the lamp in a still further adjusted position;

Figure 4 is an enlarged elevational view, partly in vertical section, of the universal joint construction; and

Figure 5 is an enlarged sectional detail of a portion of the structure shown in Figure 4.

Referring now more particularly to the drawing, it will be observed that the standard for the "sun-ray" lamp unit 10 or the like comprises generally a vertically extending pedestal 11 having a suitable base 12 at the bottom end thereof and to the upper end of which is secured, by the means to be presently described, a laterally extending arm 13 of preferably goose-neck shape. Secured to the outer extremity of the arm 13 and adapted to be carried thereby is the lamp unit 10.

Suitably secured to the upper extremity of the pedestal 11 is a yoke or bracket 14 having substantially parallel, vertically extending side bars 15—16, the upper ends of which are preferably joined together by the transversely extending bar 17 to afford requisite rigidity and strength to the yoke 14. A cross bolt 18 may also be provided for interconnecting the lower portions of the side bars 15—16.

Fixedly secured to the inner surface of one of the side bars, in the present instance, the side bar 16, is a member 19 having a spherical seat or depression 20 in the inner surface thereof. The outer surface of this member 19 is disposed flatwise against the inner surface of the bar 16 and is permanently and fixedly secured thereto by the screws 21 or other securing elements.

Adjustably secured to the opposite side bar 15 in axial alignment with the member 19 is a second member 22, the latter member being also provided with a spherical seat or depression 23 in the inner surface thereof. This member 22 is axially movable toward and away from the inner surface of the side bar 15 to thereby vary the effective distance between the aligned spherical seats of the members 19 and 22 for a purpose which will be apparent immediately hereinafter.

As appears most clearly in Figures 4 and 5, the side bar 15, upon which the member 22 is adjust-

ably mounted, is provided with an aperture 24 therein coaxial with the common axis of the members 19 and 22. Secured to the outer surface of the side bar 15, by means of the screws 25 or the like, is a casing 26 the interior 27 of which is adapted to accommodate a coil spring 28. The inner end of this coil spring 28 projects through the aperture 24 in the side bar 15 and bears against the member 22. The other end of the spring 28 bears against a washer or disc 29 fitted within the internal bore of the spring casing 26. Threadedly received within the outer end of the casing 26 is a screw 30 having an exterior operating knob 31. It will be understood that by properly manipulating the screw 30 it may be axially advanced against the disc 29 to thereby increase the pressure exerted by the spring 28 against the member 22. The latter is thus constantly under a spring pressure tending to shift it toward the opposite member 19. By backing out the screw 30, the spring pressure upon the member 22 is released and the latter may be moved outwardly and into flatwise engagement with the side bar 15.

In order to prevent possible rotation of the member 22 about its horizontal axis and also to prevent axial misalignment between the member 19 and 22, the member 22 is provided with recesses 32 in the outer surface thereof for respectively receiving loosely the inner ends of the securing screws 25. In other words, the screws 25 serve the additional function of guide pins for the member 22, thus permitting axial movement of the latter but preventing rotative as well as lateral movements thereof.

From the foregoing it will be apparent that the members 19 and 22 conjointly provide a substantially spherical seat or socket within which may be accommodated, for universal movement therein, the ball of a ball and socket joint. This ball is designated by the reference numeral 33. Secured to any point on the surface of the ball 33, as at 34, is the tubular arm 13, preferably of goose-neck shape. Also secured to the ball 33 at a diametrically opposite point on the surface thereof, as at 35, is a manipulating handle 36, it being observed that this handle or grip 36 is of sufficient length to afford a substantial grasp to the operator of the unit.

From the foregoing it will be apparent that by the proper manipulation of the screw 30, the spring pressure exerted by the spring 28 against the member 22 may be increased to such extent as to cause the ball 33 to be tightly embraced by the members 19 and 22, thereby insuring the maintenance of the ball in any desired adjusted position.

In operation, in order to secure various positional adjustments of the lamp unit 10, the operator may rotate the handle about its axis to thereby direct the light rays to the left or to the right as may be desired. If it is desired to raise the light unit, it is merely necessary to depress the handle 36. Conversely, by raising the handle the lamp may be lowered, and by shifting the handle to one side or the other a corresponding change may be had in the position of the lamp. Furthermore, the arrangement is obviously such that simultaneously the handle or grip 36 may be rotated about its axis and shifted in any desired direction to effect a very nice adjustment of the lamp unit.

If a still further adjustment of the lamp unit 10 is desired, the said unit may be connected or secured to its supporting arm 13 by a ball and socket joint 37 (see Figure 1). This ball and

socket joint 37 permits a certain degree of adjustment between the lamp unit and its supporting arm 13 independently of the adjustment secured by the joint interposed between the pedestal and the arm 13.

Although the invention is not directed to any particular manner of electrically wiring the standard for supplying current to the lamp unit, it will be seen that in the present instance the pedestal 11 is of hollow construction to permit the conductor wires to be threaded therethrough, as is the lamp supporting arm 13. Preferably, the inner end of the operating handle as well as the ball 33 are bored to permit the conductor wires 38 which extend upwardly of the pedestal 11 to be projected into and through the lamp-supporting arm 13. As appears most clearly in Figure 3, enough slack in the conductor wires is provided between the upper end of the pedestal 11 and the inner end of the handle so as not to interfere with the free movement of the ball within its socket.

It will be understood, of course, that the invention is applicable to other types of lamps than that shown herein and it is therefore not intended to be limited thereto. Also, it will be understood that the invention is susceptible of various changes and modifications without departing from the real spirit or general principles thereof, and it is accordingly intended to claim the same broadly, as well as specifically, as indicated by the appended claims.

What is claimed as new and useful is:—

1. In an adjustable standard of the character described, in combination, a vertically extending pedestal, a yoke mounted at the upper end of said pedestal, a pair of opposed spherically surfaced members carried by said yoke, said members constituting conjointly a substantially spherical seat for a spherical member, a spherical member rotatably disposed between said opposed members, a lamp supporting arm secured to and carried by said spherical member, and means also secured to and carried by said spherical member for effecting the rotation thereof within its socket.

2. In an adjustable standard of the character described, in combination, a vertically extending pedestal, a yoke mounted at the upper end of said pedestal, a pair of opposed spherically surfaced members carried by said yoke, said members constituting conjointly a substantially spherical seat for a spherical member, a spherical member rotatably disposed between said opposed members, a lamp supporting arm secured to and carried by said spherical member, means also secured to and carried by said spherical member for effecting the rotation thereof within its socket, and means operatively associated with one of said spherically surfaced members for varying the pressure exerted thereby against said spherical member whereby to secure the maintenance of the latter in adjusted position.

3. In an adjustable standard of the character described, in combination, a substantially upright pedestal, a yoke arranged at the upper end thereof, a pair of laterally spaced axially aligned socket members, the facing surfaces of said socket members being provided with spherical seats, said socket members being axially movable relatively to each other, a spherical member accommodated between the spherical seats of said socket members, an elongated handle secured to and carried by said spherical member for effecting the positional adjustment of the latter, a lamp

supporting arm secured to and carried by said spherical member extending in a direction substantially opposite to that of said handle, and a lamp carried by the extremity of said arm.

5 4. In an adjustable standard of the character described, in combination, a substantially upright pedestal, a yoke arranged at the upper end thereof, a pair of laterally spaced axially aligned socket members, the facing surfaces of said socket members being provided with spherical seats, said socket members being axially movable relatively to each other, a spherical member ac-

commodated between the spherical seats of said socket members, an elongated handle secured to and carried by said spherical member extending in a direction substantially opposite to that of said handle, and a lamp carried by the extremity of said arm, said lamp having a ball and socket connection with the supporting arm therefor, and spring-pressed means tending constantly to urge said socket members into frictional contact with said spherical member. 80
